DEVICE FOR USE IN TIMING IGNITION SYSTEMS

George E. Tippett, St. Louis, Mo.

Application June 19, 1950, Serial No. 169,018

3 Claims. (Cl. 73—116)

1

The present invention relates to a novel device for use in the timing of an ignition system, particularly the ignition system of an internal combustion engine.

As is well known, one of the most important requisites for efficient and smooth engine performance is that the ignition system be so timed that the spark plug of each cylinder will fire at the end of the compression stroke.

As every automobile mechanic knows, this is a tedious operation and requires considerable skill, particularly after an engine has been dismantled for repairs, and has thereafter been reassembled.

The distributor controls the firing of the spark plugs, as is understood, and the mechanic heretofore would simultaneously manipulate the distributor, and attempt to determine by hearing which adjustment thereof produced the best engine performance.

That is to say, prior to my invention, the mechanic had to rely entirely upon his skill and sense of hearing in the timing operation, and had no definite assurance that the final adjustment decided upon by him was the best one obtainable.

The primary object of the present invention is to provide for the mechanic a device whereby he can quickly and unerringly determine the proper setting of the distributor.

A further object is to provide a device which additionally will indicate to the mechanic whether or not the distributor itself is in need of repair; whether or not the ignition coil is functioning properly; whether or not the condenser should be repaired or replaced; and whether or not the valves need attention, all as will appear hereinafter.

In performing the timing operation, the present device is substituted for any one of the spark plugs, it being common knowledge that if one plug fires at the proper time, the remainder of them will also, because of crankshaft design, and so on.

The device includes a removable adapter provided with a threaded portion corresponding to the lower threaded portions of certain spark plugs.

That is to say, the device is adapted for use in ignition timing of any known internal combustion engine, including airplane engines. Obviously however, there are differences in the size of spark plugs, so that the invention contemplates the use of adapters whereby it can be employed in the timing of every type of internal combustion engine.

The principal feature of the invention is the

2

provision of means whereby the mechanic can quickly determine the end of the compression stroke, and can thus quickly adjust the distributor, regardless of the pressure developed by the piston.

That is to say, even though the pressure built up in the combustion chamber on the upstroke of the piston may vary in each engine to which the invention is applied, nevertheless the device will visibly indicate to the mechanic just when the piston reaches its uppermost point of travel.

A more comprehensive understanding of the construction and objectives of the invention may be had from the detailed description to follow, and reference to the accompanying drawing which portrays a preferred embodiment thereof.

In said drawing:

Fig. 1 is a top plan view of the device comprising the present invention;

20 Fig. 2 is a front elevational view thereof;

Fig. 3 is a side elevational view thereof;

Fig. 4 is a vertical sectional view thereof taken on line 4—4 in Fig. 2;

Fig. 5 is a horizontal sectional view taken on

25 line 5—5 in Fig. 3;

Fig. 6 is a horizontal sectional view taken on line 6—6 in Fig. 3;

Fig. 7 is a fragmentary partially sectional view portraying the invention in use.

30 With particular reference to Figs. 1 through 4 of the drawing, numeral 10 indicates generally the device per se, numeral 12 indicates generally a removable adapter associated therewith.

The assembly 10 includes a tubular member, 35 generally designated by numeral 14, comprising a lower section 16, an intermediate section 18 of reduced diameter relative to section 16, and an upper section 20 of reduced diameter relative to section 18.

40 Said lower section 16 has formed therein a longitudinal passage or bore 24, terminating at its lower end in an enlarged, internally threaded counterbore 26, the latter being provided for a purpose to appear.

45 In fluid communication at its lower end with passage 24, is a longitudinal passage or bore 28 which extends through both the intermediate and upper sections, 18 and 20 respectively, of the member 14. The diameter of passageway 28 is larger than that of passageway 24, whereby there is provided an annular shoulder 30 which normally serves as a seat for a vertically slideable piston or plunger member 32, as shown in Fig. 4.

The intermediate section 18 has formed there- 50 in an elongated vertical slot 34, through and be-

yond which projects a pin 36 rigid with the piston member 32.

The upper section 20 terminates in an externally threaded portion 38 adapted to receive a cap member 40, which as shown, is internally threaded at 42.

Numeral 46 designates an adjustable screw, a segment of which is in engagement with the said threaded portion of the cap member 40. A kerf is provided in the upper extremity of said screw for the reception of a suitable tool, and the lower extremity thereof terminates in an annular head or spring abutment 50, which is slidable in bore 28 as shown.

Interposed in bore 28 between the bottom face of said head and the top face of piston 32, is a compression spring 52, which normally maintains the lower end of said piston in engagement with its seat 30, as portrayed in Fig. 4.

The successive reductions in the external diameter of member 14 result in the formation of a first annular shoulder portion 54, and a second similar shoulder portion 56.

Pressfitted on section 18 with its lower surface in engagement with shoulder 54, is a block of insulative material designated 58; in vertically spaced relation thereto, and pressfitted on section 20 with its lower surface in engagement with shoulder 56 is a similar block designated by numeral 60.

Supported by said blocks in laterally spaced relation relative to, but in alinement with pin 36 and slot 34, is a rod 62. Integrally formed with the upper end of said rod, or otherwise rigidly secured thereto, is a laterally projecting plug member 64.

As the drawing clearly portrays, the terminal configuration of said plug is preferably similar to that of the upper extremity of a conventional spark plug. Preferably also, but not necessarily, the projecting extremity 68 of pin 36 is pointed as shown.

The device thus far described, provides for the mechanic a lightweight and compactly designed instrument adapted to visibly demonstrate the information required by him for a superlative timing adjustment, as will appear.

There are some variations in the design of modern spark plugs, as is understood. That is to say, the diameters of the lower threaded extremities of spark plugs incorporated in, for example, a 1940 engine, may vary from their counterparts in, let us say, a 1950 engine, and so on.

To this end, the aforesaid adapter 12 is provided. It includes a body portion 68, an integral polygonal portion 70, an upwardly projecting externally threaded extension 72, a depending externally threaded extension 74, and a longitudinal passageway or bore 76. Manifestly, each adapter is identical in every respect with the exception of the external diameter of depending portion 74.

Before entering into a description of the manner in which the device is employed, attention is directed to Fig. 7 which more or less schematically exhibits a fragmentary portion of an internal combustion engine E. Shown are piston P reciprocable in cylinder C, connecting rod R, distributor D, wires W normally leading from the distributor to the spark plugs, socket S on the free end of each wire normally adapted to engage the upper extremity of a spark plug, an internally threaded aperture A normally adapted to receive the depending threaded portion of a spark plug, and valve V.

In use, the device is positioned as in Fig. 7. That is to say, a selected spark plug having been removed, and a proper adapter 12 having been inserted in member 14, the composite assembly 10-12 is substituted for the spark plug. Thereupon, socket S of the lead W for said plug is snapped into place onto member 64, whereupon the engine is started.

As piston P rises on the compression stroke, plunger 32 is also caused to rise against the force exerted by spring 52.

It is noted at this time, that preferably, said spring is compressed sufficiently only to seat the plunger 32, and that therefore, the adjustment screw 46 is provided primarily to compensate for reduced resiliency of said spring following repeated use of the device, as is understood.

It is also noted however, that when the device is to be employed in the timing of a motor having a relatively high compression potential, for example an aircraft motor, screw 46 should first be rotated to increase the resistance of spring 42, so that the pressure developed will not cause the pin 36 to strike against the upper end of slot 34.

It is further noted that except for the blocks 58 and 60, the composite device 10-12 is of metallic material; that the insulated position of rod 62 relative to pin 36 provides a spark gap indicated by numeral 78 in Figs. 3, 4, and 5; and that a spark flash across said gap will be visible at intervals when the engine is running. In other words, the device 10 functions like a spark plug, but the spark is visible.

After a few revolutions of the crankshaft, the mechanic can quickly determine the exact moment at which the compression stroke ends by observing the reciprocal movements of pin 36. In other words, said pin attains its highest elevation at that time. The object now, is to also have the spark occur at that very moment. The mechanic quickly manipulates the distributor in the usual manner until the flash coincides with the end of the compression stroke.

Thus the primary object of the invention is easily attained. And, as previously explained, it is not necessary to apply the device to more than one cylinder in order to attain this objective. In actual tests, it has been found that use of the device will reduce the time ordinarily required for an ignition timing operation, as much as eighty per cent. In addition, particularly when employed by a skilled mechanic, the invention is adapted to eliminate faulty timing.

As also previously indicated, the device 10 may be utilized to obtain other information. For example, should the spark fluctuate rapidly, this indicates that the distributor shaft is worn.

Again, should the spark fluctuate unevenly, this indicates a defective valve V. A defective coil will be indicated by sparks off the rod 62, and a defective condenser by sparks off the pin 36.

In view of the foregoing, it should be manifest that the present invention provides a comparatively simple device for facilitating a hitherto difficult operation.

The precise details of construction illustrated and described obviously admit of modifications without departing from the principles of the invention. Therefore, the invention is to be limited only by the claims which follow.

What I claim is:

1. In a device for use in timing the ignition system of an internal combustion engine: a

tubular member provided with a longitudinal passageway of small diameter in its lower portion and a longitudinal passageway of larger diameter in its upper portion, said passageways being concentric and in fluid communication with one another; an annular shoulder formed at the juncture of said passageways; means in the form of a removable hollow adapter for mounting said member in a threaded spark plug opening of said engine; a piston reciprocable in said last-named passageway; a compression spring for normally seating one end portion of said piston against the annular shoulder aforesaid; means for selectively increasing and decreasing the force of said spring; an elongated slot in the upper portion of the tubular member; a pin rigidly secured to said piston at one end with its opposite free end portion projecting through and beyond said slot; a rod supported in alignment with said slot and said pin, and slightly spaced from the free extremity of the latter, by means of spaced blocks of insulation mounted on said tubular member, the relation of said rod to said pin forming a spark gap therebetween; and a plug member integral with said rod, for engagement with a socket member on the free end of a spark plug wire.

2. In a device of the character described: means for visibly indicating the spark moment during the compression stroke of a piston incorporated in an internal combustion engine; said means including a piston slidably mounted in a tubular member provided with a longitudinal cylindrical passageway therethrough; an annular shoulder formed in said passageway, a compression spring for normally biasing said piston into engagement with said shoulder, means mounted on the tubular member for regulating the force of said spring, an elongated slot in the tubular member, a pin rigidly secured at one end to said piston and projecting through and beyond said slot, a conductor rod supported in spaced relation to the projecting end of said pin to provide a spark gap, said rod being insulated from the

tubular member; and a plug integral with said rod adapted to engage a socket on the free end of a wire leading from the distributor of said engine.

- 5 3. A device of the character and for the purposes described, said device including: a tubular member; means removably secured to the lower end thereof for mounting said member in the threaded spark plug opening of an internal combustion engine; a longitudinal passageway through said tubular member including a lower section of small diameter and an upper section of larger diameter; an annular shoulder formed by the intersection of said sections; a piston slideable in said upper section; a compression spring interposed between an abutment member and the upper end of said piston for normally maintaining the latter in engagement with said shoulder; an elongated slot formed in the tubular member; a pin rigid at one end with said piston and projecting through and beyond said slot, the projecting portion of said pin terminating in a point; a rod in alignment with said slot and pin and in spaced relation thereto for providing a spark gap between the rod and the point of said pin; means in the form of blocks of insulation mounted on the tubular member for supporting said rod in position; and a plug rigid with one end of said rod for engaging the socket on the free end of a spark plug wire.
